CLAIM

The ornamental design for a battery, as shown and described.

DESCRIPTION

FIG. 1 is a top, front, right side perspective view of a battery, showing my new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of area 9 indicated in FIG. 2;

FIG. 10 is an enlarged view of area 10 indicated in FIG. 2; and,

FIG. 11 is an enlarged view of area 11 indicated in FIG. 2. The dot-dash broken lines in the drawings illustrate the bounds of the portions shown enlarged in the drawings, and form no part of the claimed design.
